UNITED STATES PATENT OFFICE.

F. BENEDICT HERZOG, OF NEW YORK, N. Y.

TELEPHONE-EXCHANGE SYSTEM.

SPECIFICATION forming part of Letters Patent No. 292,115, dated January 15, 1884.

Application filed September 28, 1883. (No model.)

To all whom it may concern:

Be it known that I, F. BENEDICT HERZOG, of the city, county, and State of New York, have invented a new and useful Improvement 5 in Telephone, Exchange Systems, of which the following is a specification:—

My invention relates to telephone-exchange systems, where the individual subscribers are put into telephonic communication with each 10 other by an operator at a central office, through which the subscribers' circuits pass, and are controlled. Whenever a subscriber is absent from his office, and leaves no one in charge, to inform any one who may then call, at what 15 time he intends to return, or where he has gone to, he, at present, generally puts up a notice on the outside of his office door, conveying the desired information. But it frequently happens, that he is detained longer than he ex- 20 pected, or that he does not wish to return so soon, or has gone to another place; and then it is often very desirable that he should at once be able to change the notice on his door, so that it shall give the corrected information.

The object of my invention is to accomplish 25 this result, by means of an exchange system. To this end, my invention consists in providing the office of one or more subscribers with a contrivance, which can be seen from out- 30 side, when the office is locked, capable of being set by the subscriber in person, before he leaves his office, so as to indicate the time of his expected return, the place at which he is going, or any other desired information; and 35 which is, moreover, so constructed, that it is connected on the subscriber's circuit, so that it may also be operated from the central office of any telephone, or other electric-circuit exchange, and reset by the operator there, when 40 he is so directed. Then, whenever a subscriber is detained or wishes to remain away longer than he at first intended, he can, by communicating with the central office through any other subscriber's circuit, ask the operator 45 there to reset the indicator at his own office, so as to make the desired change. This, the subscriber is enabled to do by my invention.

In the accompanying drawings, I have illustrated one form of mechanism for carrying out 50 my invention; Figure 1, showing the internal construction of the indicator, placed in some

conspicuous position so that it can be seen from the outside of the office, and arranged, so that it can be set by the subscriber before leaving, and also by the operator from the central office; Fig. 2, representing the front of an indicator-box comprising several independent indicating-dials, each of which can be independently set at points prearranged to convey any desired information; and Fig. 3, representing a telephone-exchange system with the subscriber's offices provided with indicators, according to my invention.

I construct, as follows, this contrivance, by which any caller at the vacant office can obtain 65 the desired information, and which can be set, either by the subscriber at the office before leaving, or by the central-exchange operator at the subscriber's direction, when the latter is not there.

A, Fig. 1, represents a metal ratchet-disk with an arbitrary number (in this case forty-eight) of teeth, mounted on a suitable arbor or spindle, so arranged as to be impelled step by step, in the well-known manner, by the pawl D. 75 pivoted to the vibrating lever C. which is actuated by the electro-magnet B. By sending the proper number of electrical impulses over the line through the electro-magnet B. from the central office, the ratchet-disk A. may be ad- 80 vanced step by step to any desired position, and by these means the central operator is enabled to set the pointer H., which is attached to the spindle of the disk A., and moves over the exposed face of the dial, (represented by 85 the dotted lines) in any desired position. The pointer H. is also arranged so that it may be set by hand at the subscriber's office, by turning it around with the finger, or by means of a key which fits on the squared end of the 90 spindle shown. In order that the central operator may be able to tell, when the pointer is at O., so that he can set it to the proper position, I attach to the lower end of the vibrating lever C., a leaf-spring E., the free end of which bears 95 constantly upon the face of the disk A., and makes electrical connection thereto, except when a strip F. of insulating material, which is sunk flush in the disk in the path of the spring E., comes under the end of said spring, 100 and thereby breaks electrical contact between the spring and disk. The lever C. is repre-

sented as drawn forward by the electro-magnet B., the hand H., by the last vibration of the lever C., having been brought to O. on the dial. Then, when the attraction of the electro-magnet ceases, and the lever C. is drawn back by the retractile spring K., the free end of the leaf-spring E. slides over the insulating-strip F., first breaking electrical contact, and then making it again, as the point of the spring 5 comes in contact with the metal of the disk on the other side of the strip F. The main-line circuit after passing through the electro-magnet B., passes through the lever C., the leaf-spring E., disk A. and spring G., which makes 10 constant connection to the said disk. Consequently, when the lever C. is on the back stroke, and the hand H. stands at O, the circuit is momentarily broken, but closed again before the lever C. comes to rest against its back stop, so 15 as to leave the disk A. ready to be advanced step by step, as before, by impulses sent over the line from the central office. This momentary break in the circuit, being detected by the central operator, enables him to tell when 20 the hand H. has reached O. on the dial; but in order that the central operator may detect this break, it is obviously necessary that the circuit should remain closed, at the central office, during the back stroke of the lever C., and 25 therefore the vibration of the lever C., cannot be produced by simply closing and opening the circuit with a battery on the line, but must be caused by keeping the circuit closed, and increasing and decreasing the strength of current on the line, as I shall hereinafter explain.

In Fig. 3, N. represents the central office, to which are connected the several subscriber's circuits, and which is provided with the usual 30 annunciator contrivances to inform the operator there, when each subscriber calls. Each subscriber's office S. S. S. &c., is provided with an indicator, capable of being set from the central office, such as I have already 35 described and illustrated in Fig. 1. At the central office, I arrange a circuit comprising a battery O, and a circuit-closing and opening key P., which key is shunted by a high resistance telephone Q, and this circuit is arranged 40 in the well-known manner, so that it may be connected with any of the subscriber's circuits, as desired.

The practical working of my invention is then as follows:—Suppose a subscriber to have 45 set his indicator, and gone to another office, and he wishes to reset his indicator for any reason. He calls up the central office on another subscriber's circuit, and tells them how he wishes his indicator set. The central operator 50 thereupon connects the battery O. and key P. to the proper circuit, and, by depressing the key P., cuts out the high resistance telephone, and thereby increases the strength of current sufficiently to operate the electro-magnet B. 55 When the key is opened, the resistance of the telephone Q. through which the current has

then to pass, weakens the current sufficiently to allow the lever C. to drop back. Thus, the central operator advances the ratchet-disk A. step by step, and sets it at the desired point. 70 By listening at the telephone Q., the operator can detect the momentary break in the circuit, produced when the pointer has reached O, by the back stroke of the lever C.

This device also furnishes a means, whereby 75 the central operator may identify the person who requests him to reset an indicator, so as to be sure that he is a properly authorized person. In resetting the indicator when requested, the central operator can count the impulses required to bring the hand to O., from which he can deduce at once the number at which the indicator had been set. He can then require the person, requesting to have the specified indicator reset, to give this number 80 together with some other number or pass-word arbitrarily assigned to that office.; and as no one but the subscriber himself, or some authorized person, will be able to do this, the number will serve as a basis for a pass-word, 85 which must be given to the central operator, before he will consent to reset the indicator at a different point, from that at which it stood before.

If desired, the indicator may be composed 90 of several different dials, such as I have described, but arranged in the well-known manner to be all operated on the same circuit and set independently from the central office. In Fig. 2, I have shown such an indicator, comprising three dials, each of which may be numbered or marked in any manner to signify different things, as desired. The dials may all be set successively on the same circuit in the well-known manner by suitable 105 mechanism, such as that described in Letters Patent to J. U. Mackenzie, No. 273,563, of March 6, 1883.

It is not essential to my invention, that the indicating contrivances should be placed on 110 the subscriber's telephone-circuits. They may evidently be placed on circuits employed for signaling or calling, or for any other purposes, or they may be arranged on circuits of their own, and worked entirely independently of 115 any other telephonic or signaling apparatus.

I do not confine myself to an indicating contrivance or any particular form of construction, nor to any particular mode of operating such contrivance.

What I claim as my invention, and desire to secure by Letters Patent is:

1. The combination, in a telephone or telegraph exchange system, with two or more subscribers' circuits connected with the central office thereof, and telephonic or telegraphic apparatus whereby the subscribers may communicate with the central office, of indicators located at or near the offices of one or more subscribers, for indicating specified times of 125 day or other information according to the positions at which they are set, and mechanism 130

whereby the said indicators may be set by the operator from the central office, substantially as described.

2. The combination, in a telephone or telegraph exchange system, with two or more subscribers' circuits connected with the central office thereof, and telephonic or telegraphic apparatus whereby the subscribers may communicate with the central office, of indicators located at or near the offices of one or more subscribers, for indicating specified times of day or other information according to the positions at which they are set, means whereby the said indicators may be set by the subscribers at their offices, and mechanism whereby they may be set by the operator from the central office, substantially as described.

3. The combination, in a telephone or telegraph exchange system, with two or more subscribers' circuits connected with the central office thereof, and telephonic or telegraphic apparatus whereby the subscribers may communicate with the central office, of indicators located at or near the offices of one or more subscribers, for indicating specified times of day or other information according to the po-

sitions at which they are set, means whereby the said indicators may be set by the subscribers at their offices, mechanism whereby they may be set by the operator from the central office, and devices to enable the central operator to tell at what positions the said indicators have been respectively set by the subscribers, substantially as described.

4. The combination, with the metal ratchet-disk A, electro-magnet B, and lever C, for actuating the said disk step by step, of the insulating-strip F in the said disk, and the connecting-spring E carried by the lever C and bearing upon the disk A, so constructed that on the back stroke of the lever C, when the said disk is at a particular point of its revolution, the spring E slides over the strip F, first breaking the circuit and then closing it again before the lever reaches its back stop, substantially as described.

Signed and witnessed this 27th day of September, 1883.

F. BENEDICT HERZOG.
